UNITED STATES PATENT OFFICE.

HARRISON B. WALTER, OF DANVILLE, ILLINOIS, ASSIGNOR TO NATIONAL FIBRE BOX COMPANY, OF DANVILLE, ILLINOIS, A CORPORATION OF ILLINOIS.

BOX.

1,198,294.

Specification of Letters Patent. Patented Sept. 12, 1916.

Application filed November 2, 1914. Serial No. 869,867.

To all whom it may concern:

Be it known that I, HARRISON B. WALTER, a citizen of the United States, residing at Danville, in county of Vermilion and State of Illinois, have invented certain new and useful Improvements in Boxes, of which the following is a specification.

My invention relates to an improvement in boxes of the knockdown type, the special purpose of this invention being to produce a box well adapted for parcel-post and light freight shipments, and it consists in two pieces of material, the joints of which all have over or underlapping flanges.

15 In the accompanying drawings:—Figure 1 is a transverse sectional view, Fig. 2 is a horizontal sectional view, and Fig. 3 is a small sectional detail.

One piece of material is bent to form the bottom 1, the back 2, top 3, and the flaps 4 and 5 at the ends. The other piece of which the box is composed is bent to form the front 6, the ends 7 and 8, and the three flaps 9, 10, 11, and 9', 10', and 11' respectively, the front therefore supplying the place of the missing flaps, and the flaps 10 and 10' being riveted or otherwise secured to the back 2, thus constituting the sole means of attaching the two parts composing my improved box together. When closed, the flaps 4 and 5 are tucked just inside the front 6, and between it and the adjacent ends of the flaps 11, 11' and 9 and 9' respectively.

The box is easily made and at a minimum expense, is easily set up and put together, 35 has tight joints by reason of the flap over-lappage, which also add strength and rigidity to the box.

It is evident that more or less slight changes might be resorted to in the form 40 and arrangement of the several parts described without departure from the spirit and scope of my invention, and hence I do not wish to be limited to the exact construction herein set forth, but:—

45 I claim:—

A knock-down box composed of two pieces of material, one of which is cut to form a flapless center which forms the front of the box and the two ends each having a flap on 50 each of three edges, and the other cut and bent to form back, bottom and top, and flaps along the outer edges of the top and bottom, the edges of the back permanently secured to the end flaps of the ends and the flaps 55 along the ends of the top and bottom adapted to be inserted between the front and the ends of the side flaps on the ends.

In testimony whereof I affix my signature, in the presence of two witnesses.

HARRISON B. WALTER.
